FIRE DOOR

Nathan Michelman, Brooklyn, N. Y.

Application December 2, 1949, Serial No. 130,705

4 Claims. (Cl. 160—9)

1

This invention relates to automatic fire closures, such as fire doors, fire shutters, and the like, and more particularly to a fire door of the rolling type particularly adapted for use in piers, wharves and other industrial structures.

Such doors are flexible and arranged to be wound around a shaft or drum at the head or lintel of a doorway, and generally comprise a series of metallic strips, slats or panels which are interconnected for relative hinged movement, the opposite ends of such strips being guided within vertical tracks at each side of the doorway opening. The door is actuatable for opening and closing in response to operation of the door rolling mechanism by hand through the medium of a chain and gearing, and is actuatable automatically for closing by mechanism operable in response to a rise in temperature indicative of a fire.

In all of these types of doors, and particularly where they are raised manually, counter-balancing mechanism is considered essential to reduce the force necessary to raise or "roll up" the door and to govern the speed of descent to avoid injury to any one caught in the doorway opening during a door lowering movement.

The present invention is directed to an improved operating mechanism for such doors, including an improved counter-balancing means and improved automatic release features. To this end, the door winding drum or sleeve is rotatably mounted on a fixed shaft, and one or more torsion springs are connected between the sleeve and the shaft for charging, or winding, during rolling up of the door. A second shaft has a friction bearing in the inner end of the fixed shaft, and its outer end carries an axially movable first clutch member. A torsion spring is connected between the two shafts in such manner that it is charged or wound during lowering of the door, and thus acts as a counter-balance during rolling up of the door.

A second clutch member is rotatably mounted on the rotatable shaft, adjacent the first clutch member, and is connected to the door-winding drum. This second clutch member is normally meshed with gearing included in a chain operated, manual door roll-up arrangement. The first clutch member carries teeth cooperable with a pair of opposing dogs on a ring surrounding the same, said ring being pivotally mounted so that under gravity it is concentric to the axis thereof, said ring upon alternate coaction of its dogs with the teeth of said clutch being oscillatable in an arc eccentric to the axis of said

2

first clutch member. Normally, the automatic door release maintains this ring in eccentric, embracing as to one dog, but otherwise spaced relative to the first clutch member.

The automatic door release includes a pair of levers pivotally mounted on the housing for the door operating mechanism, these levers being adjustably interconnected for movement as a unit. One lever carries a weight on its free end, and both levers are held in an elevated position by the usual fusible link chain which, upon a predetermined temperature rise in the vicinity of the door, breaks to drop the levers. Of the two levers, one is secured to the shaft of a clutch engaging fork mechanism to engage the clutch members when released by the fusible link chain. The other lever is secured to a sleeve freely mounted on such shaft and carrying an eccentrically mounted roller normally holding the oscillating ring in eccentric relation to the first clutch member. When the levers drop, the roller is released to allow oscillation of the ring now maintained under gravity which, in an oscillating or rocking manner described hereinafter, controls the rate of descent of the door. In such descent, the torsion spring or springs engaged with the fixed mounting shaft and the door winding drum bias the drum to unroll the door.

One of the members of the gear train between the hand operating chain and the second clutch member is rotatably mounted on a swingable arm. This arm is normally held in a position engaging the gear member with associated gearing in the gear train by a cam roller eccentrically mounted on a weighted lever. The latter is held in an upper position by the fusible link chain. When the fusible link chain breaks, the weighted lever drops allowing the arm to fall to drop the gear member out of the gear train, the weighted lever acting further to positively move the arm downwardly. This disconnects the second clutch member, and the connected drum, from the hand chain, freeing the door dropping mechanism.

With the foregoing in mind, it is an object of the present invention to provide an improved operating mechanism for rolling doors.

Another object is to provide an improved automatic release for rolling fire closures.

A further object is to provide an improved counter-balancing arrangement in an automatic rolling door operating mechanism.

These, and other objects, advantages and novel features of the invention will be apparent from the following description and the accompanying drawings. In the drawings:

Fig. 1 is a front elevation view of a fire door embodying the invention;

Fig. 2 is a vertical sectional view of the door on the line 2—2 of Fig. 1;

Fig. 3 is a horizontal sectional view on the line 3—3 of Fig. 1;

Fig. 4 is an enlarged, partial front elevation view of part of the control mechanism;

Fig. 5 is a side elevation view of the control mechanism shown in Fig. 4;

Fig. 6 is a rear elevation view of the control mechanism;

Fig. 7 is a horizontal sectional view through the control mechanism;

Fig. 8 is an enlarged horizontal sectional view of the mechanism at the right of Fig. 7; and

Fig. 9 is an enlarged horizontal sectional view of the mechanism at the right of Fig. 7 with the clutch members in engagement.

Referring to Figs. 1, 2 and 3, door 10 may comprise a plurality of hingedly interconnected strips or slats 11 slidably in vertical tracks 12 and arranged to be wound on a drum 15 mounted within a transversely curved longitudinal draft guard 13 supported as on a lintel 14. The automatic control 20' is mounted at the right, as viewed in Fig. 1, being encased in a housing 16. Control 20' includes interconnected arms 20 and 25 supported by a fusible link chain 17 trained over a pulley 18 and including extensions such as 21 extending through guard 13. Arm 25 is weighted as at 22. The door is manually operated by a chain 23 extending from a gear housing 24 and cooperable with a chain lock 26 which may be mounted on a track 12 or on a wall 27.

Referring to Figs. 4 through 8, a normally fixed shaft 30 is mounted in a bearing 28 in an end wall 31 of guard 13 and has keyed to its outer end a drum 32 having apertures 33 adapted to receive a bolt or pin 34 mounted in a bracket 36 on wall 31. Normally, drum 32 and attached shaft 30 are held stationary, but pin 34 may be disengaged to provide for turning of shaft 30 to effect a pre-set initial charging of torsion springs 35, 37. Shaft 30 extends freely through a circular bracket 38 mounted on a bearing 39 on shaft 30 and secured to door winding drum 15.

Next to bracket 38 is a conical clutch 40, secured to drum 15 and having shaft 30 extend freely therethrough. Spring 37 is engaged with clutch 40 and with a second conical clutch 41 secured to shaft 30. Beyond clutch 41 is a third conical clutch 42 secured to shaft 30 and engaged with one end of spring 35. The other end of spring 35 is engaged with clutch 40, and springs 35 and 37 are charged during unwinding of door 10 or drum 15 so as to assist the re-winding of the door, thus reducing the amount of effort required to raise the door.

Beyond clutch 42, shaft 30 has secured thereto a circular spacer plate 43. The innermost end of shaft 30 has a socket receiving an "Oilite" friction bearing 44 in which is engaged the innermost end of a rotatable shaft 50. A torsion spring 45 is engaged with a conical clutch 46 on shaft 30 and a conical clutch 47 on shaft 50, spring 45 being charged during winding of door 10 so as to bias shaft 50 to rotate in a door unwinding direction. Through clutch mechanism to be described, shaft 50 is connected to drum 15 during automatic release of door 10 so that spring 45 assists the action of gravity in unwinding the door. Shaft 50 has a frictional fit in bearing 44 such that it is normally held against turning relative

to shaft 30 but can be relatively rotated by the application of a torque.

The outer end of shaft 50 has secured thereto a first clutch member 55 carrying a clutching ring 56 on its inner surface and having teeth 57 (Fig. 5) on its periphery. Member 55 has a channelled hub 58 which is engaged by rollers 59 on arms 61 secured to a shaft 62 mounted in brackets 63 on a wall 64 of guard 13. One end of shaft 62 is secured to the inner end of lever 25, which is connected by adjustable means 48 to lever 20.

Just beyond clutch 47, a drum 49 secured to drum 15 is keyed to a sleeve 51 rotatable on shaft 50 and supported in a bearing 52 in wall 64. The outer end of sleeve 51 has keyed thereto a second clutch member 65 having a clutch ring 66 on its outer face and gear teeth 67 on its periphery.

A sleeve 53 is freely mounted on shaft 62 inwardly of arm 25 and forming part of arm 20. Radial arms 54 on sleeve 53 support a roller 68. Roller 68 engages an arm 71 on a ring 70 which spacedly surrounds first clutch member 55 and has a pair of teeth or dogs 72, 73 cooperable with teeth 57 of member 55. Ring 70 is oscillatably mounted on a pin 74 engaged in a bracket 76 mounted on wall 64, said ring under such mounting being maintained by gravity in position concentric to the first clutch member 55. Normally, roller 68 engaging arm 71 retains ring 70 eccentric with member 55, and with dog 72 in tooth holding position.

Manual door-winding chain 23 is trained over a sprocket 77 rotatable in housing 24 and carrying a pinion 78 meshing with a gear 81 also rotatably supported on housing 24. Gear 81 is fixed to a pinion 82 meshing with a pinion 83 rotatable on a shaft 84 mounted on wall 64. An arm 85 oscillatable on shaft 84 carries, intermediate its ends, a pinion 86 meshing with pinion 84 and the teeth 67 of member 65, when arm 85 is in its upper position (Figs. 5 and 6). Arm 85 is laterally confined by a bracket 87 on wall 64 and is held in the upper position by a roller 88 on an arm 89 of a lever 90 oscillatable on a pin 91 on wall 64. The outer end of lever 90 is secured to fusible link extension 21.

Normally, the parts occupy the position shown in Figs. 4 through 8, which represent the door 10 in the rolled up position, with fusible link chain 17 holding levers 20, 25 and 90 in the elevated position. Clutch members 55 and 65 are disengaged and chain 23 is engaged with lock 26 holding the door in the upper position. In this position, springs 35 and 37 have been substantially discharged by relative rotation between drum 15 and shaft 30. As stated, these springs may, if desired, be given an initial charge by rotation of drum 32 before pin 34 is set in place.

Assuming that a fire occurs and the resulting temperature rise effects a breaking of chain 17, levers 20 and 25 drop. The lever 20 swings arm 54 counter-clockwise to disengage roller 68 from arm 71 on ring 70, permitting it to be oscillated toward concentric relation to the axis of clutch member 55. Lever 25 rocks shaft 62 counter-clockwise (Fig. 4) causing arms 61 and their rollers 59 to move clutch member 55 to engage clutch member 65. At the same time, lever 90 drops, releasing arm 85 to follow. As roller 88 moves counter-clockwise, it engages hook 92 on the other end of arm 85 accelerating and making positive the downward movement of arm 85. Such movement disengages pinion 86 from pinion 84 and teeth 67 of clutch member 65. The latter

is therefore freed from chain 23 and may rotate with clutch member 55.

The weight of the door starts drum 15 turning in a direction to lower the door. This action is assisted by the turning force exerted on shaft 20 by spring 45 which was charged during the winding up of the door, shaft 20 being connected to drum 15 through clutch 55-65. As the door lowers, clutch member 55 is turned and its teeth alternately strike dogs 72 and 73 on ring 70, which has by gravity moved toward a concentric position relative to members 55 due to release of arm 71 by roller 68. Each time a tooth 57 strikes dog 73, ring 70 is rocked or oscillated and thereby displaced in an eccentric arc relative to the axis of clutch member 55 to engage dog 72 with an opposite tooth 57 and vice-versa. This oscillation of ring 70, alternately engaging dogs 72 and 73 with teeth 57 controls the rate of downward movement of the door. During such downward movement, turning of shaft 50 relative to shaft 30, in friction bearing 44, charges springs 35 and 37.

To re-set the door, lever 90 is swung clockwise so that roller 88 engages arm 85 to raise the latter to engage pinion 86 with pinion 83 and member 65. As the gear train between sprocket 77 and member 65 is now complete, movement of chain 23 will rotate member 65 in a door winding direction. Member 55 is still engaged with member 65 so that shaft 50 being turned charges spring 45. When the door has been fully raised, levers 20 and 25 are lifted and the break in chain 17 restored. This lifting of the two levers disengages members 55 and 65 and engages roller 68 with arm 71 to restore ring 70 to the concentric position of Fig. 5. The door is now again in the operative position.

While a specific embodiment of the invention has been shown and described in detail to illustrate the application of the invention principles, it should be understood that the invention may be otherwise embodied without departing from such principles.

What is claimed is:

1. Operating mechanism for a rolling fire shutter comprising, in combination, a fixed shaft, a rotatable shaft concentrically aligned with said fixed shaft and having an end supported in an end of said fixed shaft, a drum rotatably mounted on said aligned shafts and arranged to have the shutter wound thereon, first torsion spring means secured between said fixed shaft and said rotatable shaft and charged, during winding of the door on said drum, to bias said rotatable shaft in a door unwinding direction, second torsion spring means secured between said fixed shaft and said drum and charged, during unwinding of the door, to counter-balance the door weight during winding of the door on said drum, a first clutch member secured to said rotatable shaft, a second clutch member secured to said drum, manually operable door winding means, gearing interconnecting said door winding means and said second clutch member, said gearing including an element mounted intermediate the ends of an arm pivotally mounted at one end for swinging movement in a vertical plane, gravity biased means normally maintaining said arm in a position holding said element in operative relation in the gearing, a clutch operating member biased to a position engaging said clutch members, and fire detector means restraining said gravity biased means in the arm maintaining position and said operating member in the clutch dis-

engaging position whereby, when said detector means operates upon occurrence of a fire, said gravity biased means is released to release said arm to disengage said element to uncouple said second clutch member from said winding means, and to release said operating member to engage said clutch members to couple said drum and said rotatable shaft during unwinding of the door under the influence of gravity and said first torsion spring means, said gravity biased means including an abutment engageable with said swinging arm to positively force the latter downward to disconnect said gearing.

2. Mechanism as claimed in claim 1, including means activated by said fire detector means and cooperable with said first clutch member to regulate the rate of unwinding of the door.

3. In operating mechanism for a rolling fire shutter of the type comprising a fixed shaft, a rotatable shaft concentrically aligned with said fixed shaft and having an end supported in an end of said fixed shaft, a drum rotatably mounted on said aligned shafts and arranged to have the shutter wound thereon, first torsion spring means secured between said fixed shaft and said rotatable shaft and charged, during winding of the door on said drum, to bias said rotatable shaft in a door unwinding direction, second torsion spring means secured between said fixed shaft and said drum and charged, during unwinding of the door, to counter-balance the door weight during winding of the door on said drum, a first clutch member secured to said rotatable shaft, a second clutch member secured to said drum, a gravity influenced operating member biased to engage said clutch members, and fusible fire detector means restraining said operating member to a clutch disengaging position; door speed controlling mechanism comprising, in combination, ratchet teeth on the periphery of said first clutch member, a ring spacedly surrounding said first clutch member and having a pair of circumferentially spaced dogs alternately cooperable with said ratchet teeth, said ring being oscillatably mounted relative to said first clutch member and gravity influenced to move to a position eccentric thereto to alternately engage a dog with said teeth, said operating member including holding means normally maintaining said ring concentric with said first clutch member and releasing said ring upon movement of said operating member to clutch engaging position.

4. Operating mechanism for a rolling fire shutter comprising, in combination, a fixed shaft, a rotatable shaft aligned with said fixed shaft and having its inner end frictionally engaged in the inner end of said fixed shaft, a drum arranged to have the shutter wound thereon, a bearing rotatably supporting one end of said drum on the outer portion of said fixed shaft, a sleeve rotatably supporting the other end of said drum on the outer portion of said rotatable shaft, first torsion spring means secured between said fixed shaft and said rotatable shaft and charged, during winding of the door on said drum, to bias said rotatable shaft in a door unwinding direction, second torsion spring means secured between said fixed shaft and said drum and charged, during unwinding of the door, to counter-balance the door weight during winding of the door on said drum, a first clutch member secured to said rotatable shaft, said first clutch member having ratchet teeth on its periphery, a second clutch member secured to said sleeve and having gear teeth on its periphery, manually

operable door winding means, gearing interconnecting said door winding means, and said second clutch member, said gearing including an element mounted on a swinging arm, a first weighted lever carrying a roller cam engaging said arm, in the upper position of said lever, to hold said arm in a position holding said element in operative relation in the gearing, a ring spacedly surrounding said first clutch member and having a pair of circumferentially spaced dogs alternately cooperable with said ratchet teeth, said ring having a radial abutment normally biasing the ring to swing to a position eccentric to said first clutch member to engage one of said dogs with said ratchet teeth, a rock shaft carrying a fork engageable with said first clutch member, a second weighted lever secured to said rock shaft and, in its upper position, positioning said fork to disengage said clutch members, a sleeve carrying a cam roller engageable with said abutment and mounted on said rock shaft, a third lever secured to said sleeve, said roller, in the upper position of said third lever, engaging said abutment to hold said ring concentric with said first clutch member, means adjustably interconnecting said second and third

5

10

15

20

25

levers, and a fusible link chain attached to all three levers and holding the same in the upper position, said chain breaking upon occurrence of a predetermined temperature rise, to release the levers, said first lever effecting disengagement of said gearing element to uncouple said winding means, said second lever effecting engagement of said clutch means, and said third lever effecting release of said ring so that said ring is oscillated by said dogs striking said ratchet teeth alternately to regulate the rate of unwinding of the door, said first lever including an abutment engageable with said swinging arm to positively force the latter to a gear disconnecting position.
